(57) **CLAIM**

The ornamental design for a blade support, substantially as shown and described.

DESCRIPTION

FIG. 1 is an isometric view showing the front, top and side of my design;

FIG. 2 is an isometric view showing the front, bottom and side of my design;

FIG. 3 is a front elevation view of my design;

FIG. 4 is a rear elevation view of my design;

FIG. 5 is an elevation view showing the right side of my design;

FIG. 6 is an elevation view showing the left side of my design;

FIG. 7 is a top plan view of my design;

FIG. 8 is a bottom plan view of my design; and,

FIG. 9 is an exploded view of my design for engaging with a food cutting device and supporting a blade member therein.

The portions shown in the drawings in dot and dash do not constitute part of the claim.
